CLAIM

The ornamental design for a child car seat, as shown.

DESCRIPTION

FIG. 1 is a front perspective view of a child car seat showing my new design;

FIG. 2 is a rear elevation view of the child car seat; FIG. 3 is a side elevation view of the child car seat; and, FIG. 4 is a top plan view of the child car seat.

The broken lines shown in the drawings are for illustrative purposes only and form no part of the claimed design.
